UNITED STATES PATENT OFFICE.

JAMES A. FITZGERALD, OF PHILADELPHIA, PENNSYLVANIA.

CLAMP.

SPECIFICATION forming part of Letters Patent No. 371,310, dated October 11, 1887.

Application filed March 26, 1887. Serial No. 232,560. (No model.)

To all whom it may concern:

Be it known that I, JAMES A. FITZGERALD, of Philadelphia, in the county of Philadelphia and State of Pennsylvania, have invented certain new and useful Improvements in Clamps; and I do hereby declare the following to be a full, clear, and exact description of the invention, such as will enable others skilled in the art to which it appertains to make and use the same.

My invention relates to an improvement in clamps, and more particularly to a device of that character that may be employed to hold articles of various forms while undergoing repair by gluing joints, the object being to afford a clamp that will be universal in its application, easy to affix in position, capable of rigid adjustment at any desired point, and instant release from such adjustment.

20 A further object is to provide a furniture or other clamp that is of simple, durable construction and low cost of production.

With these objects in view my invention consists in certain features of construction and 25 combinations of parts, that will be hereinafter described, and pointed out in the claims.

Referring to the drawings making a part of this specification, Figure 1 is a side view of the clamp. Fig. 2 is an end view of the device.

30 A represents the frame of the clamp. This is preferably made of metal. It is constructed having two parallel sides, A', of proper width, and an integrally-formed rear end that is at 35 right angles to the sides. The forward portion has divergent jaws A², made to extend from the sides A' and converge toward each other at suitable angles to join the outer surface of these jaws squarely, as shown in Fig. 1.

40 At opposite points, near the centers of the side walls of the clamp, proper-sized perforations are made in these sides A' to receive the shaft B, which is machine-finished to give it a true cylindrical form.

45 The ends of the shaft B are made to project beyond the outer surface of the frame A, the body of the shaft being enlarged at c, which is one of these projections, to produce a shoulder, c', that has a bearing against the outer 50 surface of the side of the frame A. A crank, B', is furnished with a handle, B², removably

secured to the outer end of the shaft B, a screw-thread being cut on a reduced part of the projection c to accommodate the crank-handle. The opposite end of the shaft B, that extends outside of the frame, is preferably squared to fit a square hole made in the ratchet-wheel C, which is placed on it, and there retained by a threaded nut, d, that tightly jams the wheel against the shoulders of the squared portion of the shaft B, in a manner to permit the easy rotation of this shaft by its handle.

A pawl, C', is pivoted to latch into the teeth of the wheel C, and is made to have a yielding contact with this wheel by the impingement 65 of the plate-spring C², which is firmly attached to the frame A.

The body of the shaft B has two perforations, e e, made through it of a proper proportionate diameter, that are adapted to receive a neatly-fitting cord or rope, D.

The rear end, A², of the frame A is provided with two holes, a a, of same diameter as that of the holes e in shaft B. The holes a a are countersunk or rounded on their edges to prevent an abrasion of the rope D, which is made to extend through them. At points b b in the bent front portions of the sides of the frame A are the holes b, the latter being also rounded on their edges to permit a free passage of the rope 80 D, which is inserted therein previous to its insertion through the holes e in the shaft B.

The rope or cord D is of such durable character as to withstand a strain within the capacity of the machine to produce, and has its 85 free ends extended a proper distance outside the holes a a, the rope ends being first passed through the holes b, then into holes e e in the shaft B, thence through the holes a a, and in this manner form a loop of the rope opposite 90 the crotched portion of the frame A, produced by the free divergent ends A² of the same.

In use the device is placed with its crotch against a portion of the article to be operated upon, the rope D is placed to encompass the portion of the article to be clamped, and the free ends of the rope are drawn to take up all the slack possible. A rotation of the shaft B by means of its crank-handle will bite the rope in the holes e by reason of its contact with the sharp edges of these holes. A continuation 100 of the operation just described will forcibly

tighten the contact of the looped portion of the rope about the piece to be clamped, and this enforced contact will be secured from relaxing until desired by the action of the ratchet-wheel C and its engaged pawl C'.

It is apparent that the application of this simple device is universal, as it can be made to clamp any object about which a rope can be placed, and if it is necessary to have the surface of compression extended broader than the rope's diameter, it can be readily effected by the interposition of pieces of board. Blocks or any other article having a flat or curved surface may be used as clamping-jacks, which may be clamped upon the object to be subjected to compression in an obvious manner.

Having fully described my invention, what I claim as new, and desire to secure by Letters Patent, is—

1. In a portable clamp, the combination, with a frame one end of which is provided with projections for preventing the lateral displacement of the clamp when in position on an article, and a shaft journaled in said frame and provided with holes, of a rope passing loosely through the holes in the shaft and adapted to be drawn through same for the purpose of taking up the slack, substantially as set forth.

2. In a clamp, the combination, with a frame having parallel sides, a rear end at right

angles to the sides, and a crotched front end, the frame being perforated for the passage of a cord or rope at two points in its rear and front walls, of a transverse shaft journaled in the sides of the frame, the shaft being perforated to receive a cord or rope at two points, and a cord or rope inserted through the holes in the frame and shaft, substantially as set forth.

3. In a clamp, the combination, with a frame having parallel sides, a rear end square with the sides, and a crotched front end, all made integral with the frame, a cross-shaft having perforations for the passage of the cord or rope, a crank-handle, a ratchet-wheel, pawl, and spring, of a cord or rope adapted to clamp an object by the revolution of the shaft and the retaining action of the ratchet-wheel, pawl, and spring, the said cord or rope passing loosely through the shaft and adapted to be adjusted to suit articles of different sizes and be locked to the shaft by the rotation of the latter, substantially as set forth.

In testimony whereof I have signed this specification in the presence of two subscribing witnesses.

JAMES A. FITZGERALD.
